HAIR DRYER

Charles Stowe Myers, Evanston, Ill., assignor to Wahl
Clipper Corporation, Sterling, Ill., a corporation of Illinois

Filed July 11, 1963, Ser. No. 75,747

Term of patent 14 years

(Cl. D86—10)

Fig. 1.

Fig. 6.

FIG. 1 is a top perspective view of a hair dryer showing my new design.

FIG. 2 is a front elevational view thereof.

FIG. 3 is a rear elevational view thereof.

FIG. 4 is a bottom plan view thereof.

FIG. 5 is an end elevational view thereof.

FIG. 6 is a longitudinal sectional view on line 6—6 of FIG. 1, the internal mechanism omitted.

The carrying strap in FIGS. 3, 4 and 5 has been shown either broken away or omitted for convenience of illustration.

I claim:

The ornamental design for a hair dryer, as shown and described.
